UNITED STATES PATENT OFFICE.

FRED FORREST PEASE, OF EAST BRAINTREE, MASSACHUSETTS.

WRENCH.

1,418,161.

Specification of Letters Patent. Patented May 30, 1922.

Application filed June 2, 1920. Serial No. 386,130.

To all whom it may concern:

Be it known that I, FRED FORREST PEASE, a citizen of the United States, residing at East Braintree, in the county of Norfolk 5 and State of Massachusetts, have invented certain new and useful Improvements in Wrenches; and I do hereby declare the following to be a full, clear, and exact description of the invention, such as will enable 10 others skilled in the art to which it appertains to make and use the same.

The present invention relates to wrenches and more particularly to wrenches employed in connection with work requiring a 15 powerful leverage.

In the construction of steel ships it is necessary to first assemble the plates and other fabricated portions of the ship and bolt these parts temporarily in position, prior 20 to the permanent connection by riveting or other means. In the preliminary bolting of the ship plates for assembling, large through bolts are employed which must not only hold the plates in position but must be capable 25 of drawing the plates tightly together in the assembling operation. As this frequently requires an actual bending of the plates themselves, it will be obvious that a powerful leverage must be exerted upon the nut 30 to bring the plates into the desired relation. In addition to finally setting the nut in position, the best form of wrench for this purpose must be capable of rapidly threading the nut upon the other bolt until the point 35 is reached where the plates or other members have to be forced into position.

Accordingly, one object of the present invention is to provide a new and improved form of wrench which shall be capable of 40 rapidly turning a nut or other member where no substantial turning moment is required and which, in addition, shall have capacity for exerting a powerful leverage upon the nut when so desired.

It is a further object of the invention to 45 provide a wrench which may be utilized in places where only a small movement of the handle is permitted and to render such a movement completely effective without having any substantial lost motion between the 50 handle and the gripping portion of the wrench.

With these objects in view the several features of the invention consist in certain 55 novel features of construction, combinations and arrangements of parts, the advantages

of which will be obvious to those skilled in the art from the following description.

In the accompanying drawings illustrating the preferred form of the invention Fig. 60 1 represents a side elevation of the improved wrench with the handle and brace member held together in the position which they occupy for rapidly turning a nut; Fig. 2 is a similar view of the wrench with the handle 65 and brace member separated in the relative positions which they occupy when the wrench is employed for exerting a powerful turning movement upon the nut; Fig. 3 is a detail illustrating a cross section in elevation 70 of the hub and connected portions of the wrench; Fig. 4 is a detail illustrating a top plan view of the wrench, Fig. 5 is detail showing a section in elevation of the wrench, taken upon the line 5—5 of Fig. 4; and Fig. 75 6 is a detail illustrating a cross section of the one-direction clutch, taken upon the line 6—6 of Fig. 5.

The wrench shown in the illustrated embodiment of the invention comprises a hub 80 member 10 having an enlarged head 11 provided with a socket cavity 12 for the reception of the nut or the head of a bolt. In the particular embodiment of the invention shown, it will be observed that this cavity 85 is rectangular to receive its correspondingly shaped nut such as is used in the connection of ship plates. Loosely journaled upon the hub of the wrench is an actuator member or arm 14 which is supported upon two 90 bushings 15 and 16 disposed upon opposite sides of a toothed surface 17 formed upon the hub. The actuator member 14 is connected with the hub through a simple and effective form of clutch mechanism of which 95 the toothed surface 17 forms one member. The cooperating clutch members are supported within a recess 18 formed within the actuator member and consist of two sliding blocks 19 and 20, each having clutch teeth 100 21 formed thereon. These blocks are slidably supported upon inclined surfaces 22 and 23 respectively formed upon the member 14 in such a manner that when the actuator member is turned in either direction 105 one of the clutch blocks 19 is moved by the correspondingly inclined face into contact with the toothed surface 17. In order to aid in the movement of the clutch blocks into operative position each block is engaged by a 110 spring 25 coiled about a pin 26 threaded in the actuator member. In the illustrated em-

bodiment of the invention the blocks are also provided with recesses 28 which receive the ends of the pins when the blocks are in an inoperative position, as shown in the case of 5 one of the blocks in Fig. 5. In order to cause the clutch to operate as a one-direction clutch in either direction, a cam member 46 is interposed between the blocks, as shown in Figs. 5 and 6, and is mounted upon 10 the inner end of a shaft 29 having a bent portion 30 adapted to engage with positioning pins 31 and 32. When the bent portion of the shaft 29 is located in position against either one of the pins 31 and 32 one of the 15 clutch blocks is held in an inoperative position so that the clutch mechanism will operate as a one-direction clutch in either a right hand or a left hand direction. When the bent portion of the shaft 29, on the other 20 hand, is located in a neutral position between the pins both clutch members will be permitted to operate and the actuator member will be automatically connected with the hub when turning in both directions. 25 In order to impart a rapid turning movement to the hub at certain times and a slower turning movement with a powerful leverage at other times, mechanism is provided for causing the operating handle to turn the 30 actuator arm directly and through the medium of a toggle member. For this purpose what may be known as a brace member 47 is provided with a forked end 48 loosely journaled upon the bushings 15 and 16 at 35 opposite sides of the actuator arm 14, the two bearing portions 33 and 34 of the brace member being shown in section in Fig. 3. The operating handle 35 is pivoted to the brace member at 37, this pivot point being 40 located at one side of the axis of the hub. The handle, in addition, is connected with the actuator member 14 through a short link 39, the link, together with the end 40 of the handle, serving as a toggle lever, the two 45 portions of which normally have the relative positions shown in Figs. 1 and 2. When the wrench is to be employed for initially threading a bolt or nut the brace member 47 is held against the handle 35 in the position 50 shown in Fig. 1, the oppositely depending sides 42 of the brace member extending down on opposite sides of the handle. In this position so long as the handle and brace member are held together, a turning movement 55 of the handle imparts a corresponding movement to the actuator arm 14, or in other words, it is as if the handle constituted an extension of the actuator arm. This permits a rapid turning movement to be imparted to the hub the arc of which corresponds to the arc of swing of the handle. 60 When a point is reached, however, at which it is desired to put considerable tension upon the bolt or nut, the brace member is freed 65 from the handle and allowed to move against

whatever rigid support may be adjacent to the wrench. A pressure upon the outer end of the handle then swings the handle about the pivot 37 and straightens the toggle, consisting of the members 39 and 40, to impart 70 a turning movement of lesser extent to the actuator arm 14. It will be obvious that the thrust, due to the straightening of the toggle in one direction is resisted by the rigid support against which the brace member 75 47 rests so that the total thrust of the toggle is utilized to exert a powerful turning leverage upon the actuator member 14 and consequently the hub of the wrench.

The clutch connecting the actuator member with the hub of the wrench is designed 80 to provide a positive lock when moved in one direction and to be readily disengaged when moved in the opposite direction. This result is insured in the illustrated embodiment of the invention by forming the teeth on the hub as a series of semi-cylindrical portions 44 which are engaged by correspondingly shaped recesses 45 formed in the faces of the clutch blocks. During movement in one direction of the actuator member these recesses register with the correspondingly shaped teeth without damage and during movement in the opposite direction the cooperating teeth and recesses are 85 quickly and surely disengaged.

It will be understood by those skilled in the art that instead of the clutch described above any desired form of clutch mechanism may be used, such as a ratchet or equivalent 100 construction which will cause the actuator member and hub to turn in unison.

While it is preferred to employ the specific construction and arrangement of parts shown and described it will be understood 105 that this construction and arrangement is not essential except so far as specified in the claims and may be changed or modified without departing from the broader features of the invention.

The invention having been described, what is claimed is:

1. A wrench comprising an actuator member, a hub, a one direction clutch adapted 115 to connect the actuator member with the hub, a handle, and connections between the handle and actuator member designed to vary the angular movement of the handle with respect to that of the actuator member.

2. A wrench comprising a hub, a brace member journaled on the hub, an actuator member, a clutch connecting the actuator member and hub, a toggle connected with the actuator member, and means for operating the toggle to turn the actuator member. 120

3. A wrench comprising a hub, a brace member and an actuator member journaled upon the hub, a one direction clutch connecting the actuator member with the hub, a handle pivoted upon the brace member, 130

and a link connecting the handle with the actuator member and designed to form a toggle in conjunction with the handle.

4. A wrench comprising a hub, an actuator member journaled upon the hub, a handle, means for causing the handle and actuator member to turn in unison, and a link connecting the actuator member with the handle and designed to form a toggle with the handle to operate the actuator member when the means are released to permit the handle to turn independently of the actuator member. 40

5. A wrench comprising a hub, an actuator member and a brace member journaled upon the hub, means for connecting the actuator member to the hub to cause them to rotate together, a handle pivoted upon the brace member at one side of the hub, and a link connecting the handle with the outer end of the actuator member. 50

6. A wrench comprising a hub, an actuator arm journaled upon the hub, a clutch adapted to connect the actuator arm with the hub, a brace member, a handle pivoted upon the brace member, and a link connecting the handle with the outer end of the actuator arm and designed to form a toggle in conjunction with the handle. 55

7. A wrench comprising a hub, an actuator arm journaled upon the hub, a clutch adapted to connect the actuator arm with the hub, a handle, a link connecting the handle with the outer end of the actuator arm and adapted to 60 form a toggle in conjunction with one end

of the handle, and a brace member journaled upon the hub and having the handle pivotally connected thereto, the brace member being designed to embrace the handle in one position and to resist the thrust of the toggle 40 consisting of the handle and link in another position.

8. A wrench comprising a hub, an actuator arm journaled upon the hub, a clutch surface having semi-cylindrical projections formed 45 upon the hub, and a cooperating clutch member supported within the actuator member and having correspondingly shaped recesses adapted to engage with the projections to lock the actuator member to the hub. 50

9. A wrench comprising a hub, an actuator member journaled upon the hub and having an inclined surface, a clutch member formed upon the hub, and a cooperating clutch member supported in the actuator 55 member upon the inclined surface and designed to lock the actuator member to the hub when moved in one direction.

10. A wrench comprising a hub, an actuator member journaled upon the hub and having oppositely inclined surfaces, a clutch member formed upon the hub, cooperating sliding clutch members received within the actuator member and supported upon the inclined surfaces, and a cam member supported 60 between the sliding clutch members and adapted to maintain either member in an inoperative position. 65

FRED FORREST PEASE.
